(57) **CLAIM**

The ornamental design for a toy vehicle, as shown and described.

DESCRIPTION

FIG. 1 is a front, right and top perspective view of a toy vehicle, showing my new design;

FIG. 2 is a rear, left and bottom perspective view thereof;

FIG. 3 is a front, right and top perspective view of the open state of the carriage;

FIG. 4 is a right view thereof;

FIG. 5 is a left view thereof;

FIG. 6 is a front side view thereof;

FIG. 7 is a rear side view thereof;

FIG. 8 is a top plan view thereof;

FIG. 9 is a bottom plan view thereof; and,

The broken lines shown in the drawings illustrate portions of the toy vehicle that form no part of the claimed design.
